PROTECTIVE CAP FOR ELECTRICAL OUTLET

Henry Nakagawa, San Carlos, Calif. (% Prodeco, 521
Marine View Ave., Belmont, Calif. 94002), and
Richard D. Low, % R. D. Low Associates, P.O. Box
1636, San Mateo, Calif. 94401

Filed Dec. 5, 1969, Ser. No. 20,371

Term of patent 14 years

Int. Cl. D8—03

U.S. Cl. D8—184

FIG. 3.

FIG. 1.

FIG. 2.

FIG. 1 is a perspective view showing our protective cap for electrical outlet; the view from the opposite side is similar;

FIG. 2 is a fragmentary sectional view through the cap, taken substantially along the line 2—2 of FIG. 1;

FIG. 3 is a perspective view thereof showing a modified form.

The broken line disclosure of hinge ears in FIG. 3 is for illustrative purposes only.

We claim:

The ornamental design for a protective cap for electrical outlet, as shown and described.
